(57) **CLAIM**

The ornamental design for a fluid distributor, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a fluid distributor showing our new design in a first position of use;
FIG. 2 is a left side elevational view thereof; the right side elevational view being a mirror image thereof;
FIG. 3 is a top plan view thereof;
FIG. 4 is a bottom plan view thereof;
FIG. 5 is a rear elevational view thereof;
FIG. 6 is another perspective view thereof in a second position of use; and,
FIG. 7 is a left side elevational view of FIG. 6.

(Continued)

The broken lines in the drawing depict portions of the fluid distributor that form no part of the claimed design.
